FLOOR CLEANING MACHINE

John W. Gardner, Richmond Hill, N. Y.

Application June 6, 1945, Serial No. 597,870

1 Claim. (Cl. 242—55.2)

1

This invention relates to floor cleaning or dusting machines, and aims to provide such a machine utilizing a roll of paper such as, for instance, that which is commonly available for use as paper towels, for wiping up or gathering dust from smooth-surfaced floors such as wood, linoleum, oil cloth, tile, etc. The dust which is thus gathered is passed along with the paper to which it clings on to a winding roller where the paper with the dust accumulation thereon is wound into a roll which is then thrown away, whereby any need to clean the device or any part of it (as is necessary, for instance, in the case of floor mops or carpet sweepers) is eliminated.

Another object of the invention is the provision of such a device which is simple in construction and operation, economical in use, and inexpensive in cost of manufacture and maintenance.

The above broad as well as additional and more specific objects will be further clarified in the following description, wherein characters of reference refer to like-numbered parts in the accompanying drawings. It is to be understood that the drawings are intended for the purpose of illustration only, and that it is neither desired nor intended to limit the scope of the invention to the specific details of construction shown and described excepting insofar as they may be deemed essential to the invention.

Referring briefly to the drawings, Fig. 1 is a perspective view of the machine.

Fig. 2 is a plan view of the same with parts broken away and partly in section on the line 2—2 of Fig. 3.

Fig. 3 is a side elevational view of the machine.

Fig. 4 is a fragmentary enlargement of Fig. 3, showing the rear portion of the frame, with parts omitted.

Fig. 5 is a perspective view of a fragment of the winding roller and its pinion or ratchet, illustrating the means for securing the leading edge of the paper from the roll of paper, thereon.

Referring in detail to the drawings, the numeral 10 indicates the frame of the machine which comprises a pair of vertical side members 11 and 12 united at the top by a cross member 13 which is positioned somewhat rearward of the midpoint of the length of the side members so as to provide a degree of resiliency or separability between the forward ends 14 of the frame sides 11 and 12. Bosses 15 and 16 are secured in axial alignment against the inner sides of the side members 11 and 12 near the forward ends 14 thereof. The numeral 17 indicates a length or roll of paper which is purchased in the market wound upon

2

a cardboard drum 18. It is apparent that the roll is readily mounted on the bosses 15 and 16 by slightly separating the frame ends 14 to slip the drum 18 on the bosses.

5 The depth of the rear ends 19 and 20 of the sides 11 and 12 are reduced by cutting away the lower portions thereof at 21 and 22, respectively, the reduced ends 19 and 20 thus constituting rearwardly extending tongues having flat bottom surfaces. Near the reduced end 19 of the side 11 a bore 23 is provided for the rotatable reception of a pin 24 on one end of a roller or winding drum 25. The other end of the roller 25 has a staff 26 projecting therefrom, provided with a pinion or 15 ratchet 27 on its extremity.

The cut-out 22 of the frame member 12 is continued upward in a forward direction at 28 to provide a tongue 29 along the lower edge of the member. The upper edge of the tongue 29 may be 20 substantially horizontal, and at a position thereon in axial alignment with the bore 23 a semi-circular recess 30 is cut down thereinto. The portion of the staff 26 between the drum 25 and the pinion 27 is adapted to rest rotatably in the 25 recess 30. A leaf spring 31 is secured against the lower surface of the reduced rear end 20 of the member 12 and extends over the staff 26, normally urging the latter to remain in the recess 30.

With the drum 18 mounted in position at the 30 front of the frame 10, the paper 17 thereof is passed under the cross member 13 and around the roller 25 in a counter-clockwise direction. The leading end of the paper 17 is secured to the drum 25 in the following manner. Intermediate the 35 length of the drum a recess or slot 32 is cut thereinto, as shown in Fig. 5. A spring clip 33 is bent to form at one end a finger 34 which is frictionally insertable into and removable from the slot 32, and at the other end a rounded tongue 35 having 40 the contour of the drum 25. With the leading edge 17a of the paper 17 positioned as shown, the clip 33 is forced down into the recess 32 so that the tongue 35 thereof overlaps the edge 17a and thus clamps the same against the drum. To remove the edge 17a from the drum it is simply 45 necessary to lift up the resilient tongue 35, or the entire clip may be removed if desired.

A yoke 36 has arms 37 and 38 whose extremities are bent to form pins 39 which register pivotally 50 in aligned bores 40 through the sides 11 and 12. A socket 41 on the yoke 36 is receptive of the end of a stick or handle 42.

The arm 38 of the yoke 36 has pivotally secured thereto near the lower end thereof an elongated 55 pawl 43 whose nose 44 is adapted in the well

known manner to engage the teeth of the ratchet 27 when the pawl is moved in a forward direction (with respect to the frame 10) and to ride over the teeth when it is moved in the opposite direction.

In use, with the edge 17a of the paper 17 secured to the drum 25 as above described, the machine is pushed along and over the floor 45. Because of the relative smoothness of the floor, there will be insufficient friction between the floor and the contact lines or surfaces of the paper to provide a tractive grip on the paper in contact with the floor; hence, neither roller will rotate and the machine will slide across the floor as a rigid unit. In this operation the dust on the floor clings to the paper, and, as is apparent, the forward roller provides one side of the paper 17 in contact with the floor while the rear roller provides the other side of the paper in such contact. Then, at the desire of the operator and when, in his judgment, new and clean paper surfaces should be presented against the floor, he swings the handle 42 upward through an arc, thereby causing engagement of the pawl 43 with the pinion 27 to turn the latter through an arc sufficient to wind up a length of paper 17 on the drum 25 and to unwind a similar length from the drum 18. As this operation is repeated, the dust-covered paper 17 is wound onto the drum 25; and when the operation of cleaning the floor has been completed, the pinion 27 may be given a few turns by hand to completely wrap the dust in the roll of paper on the drum 25. The operator may then, if he desires, tear the paper between the rolls and remove the rear roll, lift it out of its bearings against the spring 31, remove and throw away the dust-covered paper from the drum 25, and reinsert the drum into the machine in an obvious manner to get it ready for the next cleaning. Or, he may simply leave the rear roll in the machine after each cleaning of the floor and use up the entire roll of paper 17 until he removes the rear roll and discards the soiled paper. In either case the soiled paper is simply thrown away, whereby any need to clean the wiping means of the machine is eliminated.

Obviously, modifications in form and structure

may be made without departing from the spirit and scope of the invention.

I claim:

5 In a frame having a front end and a rear end and including a pair of spaced parallel upright side members extending substantially the length of the frame, the rear end of one of said members having a horizontal bore, the rear end of the other of said members having the lower corner thereof 10 cut out thereby providing a rearwardly extending tongue from the upper portion of said other of said members with said tongue positioned above said cut out, said tongue having a flat bottom surface, said other of said side members having 15 an additional cut out extending through the underside of said tongue at the base thereof and upward and forward to provide a second rearwardly extending tongue on the lower edge thereof, said last-named tongue having a substantially semi-circular recess cut down into the upper surface thereof in alignment with said bore, a drum having a pin on one end registering in said bore and having a staff on the other end removably resting in said recess, a leaf spring having one end secured to said flat bottom and extending forward into said last-named cut out and contacting the upper surface of said staff thereby normally urging said staff into said recess.

JOHN W. GARDNER.
